GUN ACTUATOR

Jacques Gustave Méjean, Geneva, Switzerland, assignor, by mesne assignments, to General Aircraft Equipment, Inc., South Norwalk, Conn., a corporation of Connecticut

Application June 16, 1941, Serial No. 398,351
In France February 1940

4 Claims. (Cl. 121—48)

This application relates to an expandible bellows device and particularly an expandible bellows device for use in a system for firing rapid-firing guns such as machine guns and light automatic cannon.

This application is a continuation-in-part of my co-pending application S. N. 378,285, filed February 10, 1941. In that application I describe a system for controlling the firing and recharging of machine guns and the like, particularly such guns are adapted to be mounted on aircraft. The system there described is an electrical-pneumatic system in accordance with which a trigger or other element on the gun adapted to cause firing is moved by an expandible bellows device supplied by compressed air or other medium under pressure from a source carried on the aircraft, the admission of the medium under pressure to the bellows being controlled by an electrically actuated valve device.

The present invention is directed specifically to a bellows-type actuator of the type shown in that application as disposed on the gun, and which has a portion adapted to be connected with the firing mechanism of the gun to actuate the same when the device is supplied with compressed air or some other medium under pressure.

One of the objects of the invention is to provide a device of the type referred to which is particularly adapted for use in aircraft, and which operates equally as well regardless of the altitude to which it may be subjected when, for example, it is used for guns mounted on aircraft.

Another object of the invention is the provision of a bellows device for causing the initial firing of an automatic rapid-firing gun, and which is extremely sensitive and accurate in operation. Because of its constructional form the invention, particularly when used with the system described in my co-pending application referred to above, is so sensitive as to permit the firing of one shot at a time even when the gun has a rate of fire as high as 720 shots per minute.

Still a further object of the invention is the provision of a device of this type which is of simple construction, is made of relatively few parts, and is capable of being assembled and disassembled and replaced readily.

Other objects of the invention will become more apparent from the following description and claims when read in conjunction with the accompanying drawing, in which:

Figure 1 is a section on the line 1—1 of Figure 2;

Figure 2 is a side cross-sectional view of one form of the invention; and

Figure 3 is a sectional view taken on the line 3—3 of Figure 2.

5 In the drawing the reference numeral 10 indicates a supporting member for the actuating mechanism. The supporting member is adapted to be detachably secured to the gun (not shown). A casing 12 is threaded to the supporting member 10 as at 14. The casing is preferably cylindrical, as shown, and the lower portion thereof is of stepped construction to provide a concentric spring-receiving portion 16, and a smaller concentric actuating rod receiving portion 18, as clearly shown in Figure 2. The casing 12 and the supporting member 10 together form a protective housing for the bellows arrangement which will now be described.

Within the housing and mounted in a circular 20 recess in the supporting member 10, is a circular member 20 which is provided with an L-shaped passage 22 (see Figures 1 and 2). The circular member 20 is provided with a threaded opening 24 which connects with the passage 22. This

25 threaded opening receives a tube 26. The tube 26 has a tube 28 mounted thereon and at right angles thereto. The end of tube 28 is in the form of an annulus so as to fit on the tube 26 and is held in place on the tube 26 by being 30 pressed between a circular flange 30 on the tube 26 and a cap 32 threaded on the end of tube 26. Suitable packing 34 is provided as shown, to make the connection air-tight. Tube 26 is provided with openings 27 establishing communication 35 between the two tubes. The tube 28 leads to a source of compressed air or other medium under pressure (not shown). In this manner the compressed air when supplied may be passed through the tube 28, the tube 26, the L-shaped passage 22 and thus to the interior of the casing 12.

The circular member 20 is provided with a central opening in which is disposed a bearing 36 adapted to receive the actuator rod 38 with a sliding fit. The other end of the rod 38 passes through an opening 40 in the rod receiving portion 18 of the casing 12. The rod 38 is thus mounted for sliding movement in the direction of its longitudinal axis. The circular member 20 is also provided with a cut-out 42 for the purpose of making it lighter.

45 Within the casing 12 is a member 44 which has a circular opening therein to permit it to surround the rod 38 to which it is rigidly secured by 50 means of the screw 46. The member 44 is pro-

vided with an outer annular flange 48 which extends laterally from a portion 49 bent to form a deep annular space 50. The inner wall of the bent portion 49 is spaced from the rod 38.

A generally cylindrical flexible corrugated metal tube 52 is disposed within the casing 12 with its upper edge rigidly sealed to the member 20 as by welding or the like. The lower edge of the corrugated tube 52 is likewise sealed to the flange 48 of the member 44. Another smaller tube 54, similar to tube 52 and concentrically disposed with respect to tube 52, has its upper edge sealed to the lower surface of the member 20 and its lower edge sealed to an inwardly projecting flange 56 forming part of the member 44. The lower surface of this flange, in turn, abuts a flange 58 on the rod 38 and thus aids in securing the member 44 to the rod.

A coil spring 60 is disposed with one end within the annular space 50 formed by the bent portion 49 in the member 44. The other end of the spring is disposed within the spring receiving portion 16 of the casing 12.

From the structure described it should be clear that the corrugated tubes 52 and 54, and the member 44 constitute an expandible bellows arrangement, which, when supplied with compressed air or the like through the L-shaped passage 22, will expand downwardly (Fig. 2) against the action of the spring 60, and in so expanding will draw down with it the rod 38.

When the device is mounted on a gun, the upper end of the rod enters a portion of the gun where it is secured in such a manner (not shown) that downward movement of the rod fires the gun. After the gun is fired, the compressed air in the bellows is permitted to escape back through tube 28 by a valve device (not shown), and this permits the bellows to contract under action of the spring 60 and thus returns rod 38 to its normal position. The lower end of the rod 38 may be provided with an opening 62 to permit a cord or cable to be attached thereto so that it may also be operated manually by pulling the cable downwardly.

The device described possesses many advantages. It is, first of all, of simple construction and is made of relatively few parts and may be easily manufactured, assembled, and disassembled. Moreover, the particular bellows arrangement shown, with its welded air-tight construction, and with the bent portion 49 of the member 44 occupying a considerable amount of the space between the inner and outer walls of the bellows, renders the device capable of operation with only a small amount of compressed air or other medium. Still further, this last mentioned factor renders the action of the bellows very quick and very accurate.

While obviously the device shown and described may be used in other systems and for other purposes, it is believed to have special advantages and to be admirably adapted to the type of system for firing guns described and claimed in my co-pending application S. N. 378,285, of which as stated this present application is a continuation-in-part.

Moreover, it should be understood that changes in structure and arrangement may be made without departing from the essential concept of the invention, and that the invention should not be limited to the embodiment shown and described except as may be indicated by the claims which follow.

I claim:

1. An expandible bellows type actuator adapted to be operated by a medium under pressure and comprising, a support, a cylindrical bellows wall, one end of which is sealed to said support, a closure member sealed to the other end of said bellows, a smaller cylindrical bellows wall disposed concentrically with respect to said first bellows wall, one end of said smaller bellows wall being sealed to said support and the other end being sealed to said closure member, said closure member being provided with a flange extending partially into the annular chamber formed by said concentric bellows walls passage means in said support for admitting a medium under pressure to the interior annular chamber between said larger and smaller cylindrical walls to expand the bellows formed by said walls and said closure member, actuating means for urging said bellows to contracted position, said actuating means comprising a resilient member, said resilient member being adapted to engage said flange with one of its ends, the other of said ends being adapted to abut against said support, and an actuating member secured to said closure member to move therewith as the bellows expands and contracts, said actuating member passing through an opening in said support and through a central opening in said closure member within and spaced from the circumference of said smaller cylindrical bellows wall.

2. A bellows type actuator comprising, a support, said support having an opening therein, a rod slidably mounted in said opening and having an end adapted to actuate, when moved, the means to be actuated, a cylindrical corrugated bellows wall, one end of which is sealed to said support, a smaller cylindrical corrugated bellows wall likewise sealed at one end to said support, both of said bellows walls being disposed concentrically surrounding said rod, a closure member sealed to the other ends of said bellows walls to close the annular space therebetween, said rod being secured to said closure member centrally of the latter, means for admitting compressed air to the annular space between the cylindrical bellows walls to expand the bellows formed by said walls and closure member, spring means acting on said closure member in a direction urging said bellows to contracted position, a casing enclosing the bellows, said closure member having a portion bent to form an annular recess extending deeply within the annular space between the bellows walls, said spring means having one end disposed within said recess and the other end supported by said casing.

3. A bellows type actuator comprising a substantially hollow casing, said casing being provided with a pair of oppositely disposed aligned openings, an actuating member slidably mounted in said openings, an annular supporting member within said casing, said annular member having a substantially inverted U-shaped cross section and being secured to said actuating member in coaxial alignment therewith, the arms of said inverted U-shaped member being spaced from said actuating member, each free end of said arms being provided with a radially extending flange, a corrugated metallic bellows disposed within said casing and in coaxial alignment with said actuating member, a second corrugated metallic bellows disposed concentrically with respect to said first-said bellows, each of said bellows having one of its ends sealed to a wall of said casing, the other end of each of said bellows being sealed to one of said flanges, spring means for urging said bel-

lows in one direction, said means having one of its ends abutting the leg of said inverted U-shaped member, the opposite end of said spring means abutting a wall of said casing, and means for admitting a medium under pressure to the space between said bellows.

4. A bellows type actuator comprising a substantially hollow casing, said casing being provided with a pair of oppositely disposed aligned openings, an actuating member slidably mounted in said openings, a supporting member secured to said actuating member in coaxial alignment therewith and extending radially therefrom, a corrugated metallic bellows disposed within said casing and in coaxial alignment with said actuating member, a second corrugated metallic bellows

disposed concentrically with respect to said first-said bellows, each of said bellows having one of its ends sealed to a wall of said casing, the other end of each of said bellows being sealed to said supporting member, spring means for urging said bellows in one direction disposed intermediate said bellows, said spring means having one of its ends abutting a flange formed on said supporting member, said flange being adapted for restricted movement between said bellows in a direction parallel to the longitudinal axis of said actuating member, the opposite end of said spring means abutting a wall of said casing, and means for admitting a medium under pressure to the space between said bellows.

JACQUES GUSTAVE MÉJEAN.
